UNITED STATES PATENT OFFICE.

JOSEPH J. HAYES, OF ELKHART, INDIANA.

TOY GAME.

Application filed November 8, 1922. Serial No. 599,699.

To all whom it may concern:

Be it known that I, JOSEPH J. HAYES, a citizen of the United States, residing at Elkhart, in the county of Elkhart and State 5 of Indiana, have invented new and useful Toy Games, of which the following is a specification.

The object of my invention is to provide a novel, simple, interesting and durable toy 10 in the nature of a ball game, utilizing one rubber ball for releasing another which is discharged by a spring mechanism, the game being played in accordance with rules simulating a regular base ball game. I attain 15 these and other objects of my invention by the mechanism disclosed in the accompanying drawings, in which—

Figure 1 is a side elevation of the invention set ready for playing;

20 Fig. 2 is a top plan view of same; and

Fig. 3 is an end elevation from the trigger end of the device.

Like numerals designate like parts in each of the several views.

25 Referring to the accompanying drawings, I provide a suitable base 1, on one end of which is rigidly secured the base extension 2 by screws or in any other suitable manner. Attached to base extension 2 is a suitable 30 wire spring 3 having its ends 5 bent inwardly and engaging in the base extension 2, as shown in Fig. 2. I provide suitable staple 6 to securely fasten the end of the spring on the base extension. Spring 3 is provided 35 with a coiled portion 4, and with an offset loop portion 7 suitably shaped to receive a rubber ball, as shown in Fig. 1. Attached to the end of base 1 at a suitable distance from the base extension 2, I provide a spring 40 trigger 8 affixed to base 1 in some suitable

manner, as by screw 9. Member 8 is provided with a suitable bent or slightly hooked end 10, releasably engaging the loop portion 7 of spring 3, as shown in Fig. 1.

In playing the game, the spring 3 is compressed so that loop 7 will extend horizontally toward the rear of the base and be releasably engaged by the spring trigger or lock spring 8. A rubber ball is placed on loop 7 and persons playing stand at a given 45 distance from it and pitch another ball at the stationary rubber ball on the game apparatus. If struck, it naturally depresses the spring loop 7 and disengages it from the spring trigger 8, allowing the spring 3 to 50 throw the ball forward automatically toward the player. The person pitching tries to catch the ball and there are, of course, rules governing the game, whereby to make it simulate the requirements of base ball. It 55 is of course a game which can be played indoors and in an ordinary sized room in winter, or on the lawn in summer.

What I claim is:

In a toy game of the class described, the 60 combination of a base, an upstanding extension affixed to the base, a wire spring having inwardly turned ends engaged in the base extension, means bracing the spring on the base extension, the spring having opposite 65 coiled portions and having an outwardly extending loop portion of suitable size for receiving a ball, and a spring trigger affixed to the opposite end of the base from that on which the extension is positioned, said 70 spring trigger having a suitably bent end to releasably engage the central portion of the 75 spring loop described above.

JOSEPH J. HAYES.
